CLAIM

The ornamental design for the interior vehicular rearview mirror display element, as shown and described.

DESCRIPTION

FIG. 1 is a front elevation view of a first embodiment of the interior vehicular rearview mirror display element showing our new design;

FIG. 2 is a rear elevation view of the mirror display element of FIG. 1;

FIG. 3 is a right end elevation view of FIG. 1, which is a mirror image of the left end elevation view;

FIG. 4 is a bottom plan view of FIG. 1;

FIG. 5 is top plan view of FIG. 1;

FIG. 6 is a front elevation view of a second embodiment of the interior vehicular rearview mirror display element showing our new design;

FIG. 7 is a rear elevation view of the mirror display element of FIG. 6 having remaining views identical to those views shown in FIGS. 3-5;

FIG. 8 is a front elevation view of a third embodiment of the interior vehicular rearview mirror display element showing our new design;

FIG. 9 is a rear elevation view of the mirror display element of FIG. 6 having remaining views identical to those views shown in FIGS. 3-5;

FIG. 10 is a front elevation view of a fourth embodiment of the interior vehicular rearview mirror display element showing our new design;

FIG. 11 is a rear elevation view of FIG. 10;

FIG. 12 is a right end elevation view of FIG. 10 which is a mirror image of the left end view;

FIG. 13 is a top plan view of FIG. 10;

FIG. 14 is a bottom plan view of FIG. 10;

FIG. 15 is a front elevation view of a fifth embodiment of the interior vehicular rearview mirror display element showing our new design;

FIG. 16 is a rear elevation view of the mirror display element of FIG. 15 having remaining views identical to those views shown in FIGS. 12-14;

FIG. 17 is a front elevation view of a sixth embodiment of the interior vehicular rearview mirror display element showing our new design; and,

FIG. 18 is a rear elevation view of the mirror display element of FIG. 17 having remaining views identical to those views shown in FIGS. 12-14.

The broken lines shown on the drawing figures are for illustrative purposes only and form no part of the claimed design.
